UNITED STATES PATENT OFFICE.

WILLIAM H. BANFIL, OF WATERTOWN, MASSACHUSETTS.

CHEMICAL FIRE-EXTINGUISHER.

1,298,157.

Specification of Letters Patent. Patented Mar. 25, 1919.

Application filed July 29, 1918. Serial No. 247,132.

To all whom it may concern:

Be it known that I, WILLIAM H. BANFIL, a citizen of the United States, residing at Watertown, county of Middlesex, State of Massachusetts, have invented an Improvement in Chemical Fire-Extinguishers, of which the following description, in connection with the accompanying drawing, is a specification, like characters on the drawing 10 representing like parts.

This invention relates to improvements in chemical fire extinguishers of the class in which a reservoir is provided for an alkaline solution and the bottle of acid retained 15 in the reservoir normally in upright position but adapted when the extinguisher is to be used to be inverted and discharge its contents into the alkaline solution thereby to generate a sufficient gas to force the contents of the extinguisher through a suitable nozzle. In such extinguishers a stopper for the acid bottle is provided which normally rests upon the mouth of the bottle and has the stem extending into the neck thereof. 20 means being provided for permitting the stopper to fall away from the mouth of the bottle when the extinguisher is inverted for use. When thus inverted the stopper falls away from the mouth of the bottle and the stem which is more or less withdrawn from the neck of the bottle serves to restrict the flow of acid and also to distribute the same uniformly thereby controlling the generation 25 of gas and causing the generation of gas to proceed with substantial uniformity throughout the area of the reservoir. In fire extinguishers of this class the stopper-distributer usually comprises a mass of porcelain or other vitreous material which is 30 adapted to seat upon the mouth of the bottle the stem being a dependent integral central extension thereof. The stopper-distributer usually is contained in a cage depending from or connected to the cover of 35 the extinguisher and is removed with the cover when the extinguisher is to be refilled.

When the cover is thus removed the stopper falls to the bottom of the cage so that the stem projects and frequently as the 40 cover is being carried aside or laid down the stem is broken or chipped so that when replaced the remainder thereof fails to serve its function of properly seating the stopper upon the mouth of the bottle and when the 45 fire extinguisher is inverted the mutilation or absence of the stem causes failure of

proper restriction and distribution of the acid flowing from the bottle. The object of the present invention broadly speaking is to provide a chemical fire extinguisher of 50 the class described with means for insuring proper closure of the acid bottle and proper distribution of the contents of the bottle when the extinguisher is placed in use by inversion. More specifically the object of 55 the invention is to provide the cage for supporting the stopper-distributer with means for preventing the stem of said stopper-distributer from extending beyond the boundary of the cage so that it will be protected 60 from harm. Other objects of the invention will more fully appear from the accompanying description and drawings and will be particularly pointed out in the appended 65 claims.

A preferred embodiment of the invention 70 is illustrated in the accompanying drawings in which

Figure 1 is a vertical longitudinal section of the upper portion of the fire extinguisher 75 illustrating my invention applied thereto;

Fig. 2 is a vertical sectional view of the cage and stopper-distributer, and

Fig. 3 is a transverse sectional view on the line 3—3 of Fig. 1.

The fire extinguisher illustrated in the accompanying drawings comprises a cylindrical reservoir 1 having a contracted neck portion 2 to which is secured a bottle holder comprising a sleeve 3 having downwardly extended rods 4 supporting at their lower end a base preferably in the form of a ring 5 which serves as a seat for the lower end for the bottom of the bottle 6. A ring 7 may also be secured to the rods 4 intermediate 80 of their length to strengthen the construction of the bottle holder and also provide additional means for engaging the wall of the bottle. The receptacle is provided with a cover 8 having an annular extension 9 adapted to be readily grasped by the hand 85 and is provided with a downwardly extending screw threaded flange 10 which engages suitable screw threads 11 upon the sleeve 3 of the bottle support 4, the end flange 10 90 preferably abutting against the contracted extension 2 of the reservoir 1. The cover 8 is also provided with a downwardly extending flange 12 provided with means for adjustably and removably supporting the cage 110 for the bottle stopper-distributer. The preferred form of cage illustrated herein com-

prises a sleeve 13 having screw threads engaging companion screw threads upon the flange 12.

Downwardly depending arms 14 are connected to or preferably formed integral with the sleeve 13 and are connected at their lower ends to a ring 15 which may also conveniently be made integral with the arms 14 and sleeve 13. The stopper-distributer comprises a substantially cylindrical mass 16 of material of considerable weight—preferably vitreous material such as porcelain—and is of such size as to slide readily within the cage formed by the sleeve 13 and downwardly extending guiding arms 14. The stopper-distributer preferably has a concaved or recessed seat 17 adapted to engage and closely seat upon the mouth of the bottle and is also provided with a central 20 downwardly extending stem 18 adapted to enter the mouth of the bottle.

In order to prevent the stem 18 projecting from the cage when the cover is removed, the arms 14 are formed with thickened lower 25 portions 19 presenting shoulders 20 to engage the edge of the seat 17 of the stopper-distributer 16 when the cover is removed from the receptacle but it will be obvious that other means may be provided to accomplish this purpose.

When the extinguisher is to be filled the cover 8 is unscrewed from the bottle support 3 and wholly removed from the extinguisher. An alkaline solution or means to form an 35 alkaline solution is then introduced into the reservoir 1. The acid bottle 6 is likewise removed and filled and then inserted within the bottle support as illustrated in the drawings. The cover is then replaced and 40 screwed down thus permitting the stopper-distributer to rest upon the neck from the mouth of the bottle with its extension 18 projecting into the neck thereof.

When the extinguisher is to be used it is 45 inverted and the bottle 6 falls by gravity until its shoulder 21 engages and rests upon the ring 15 of the cage for the stopper-distributer. The stopper-distributer being of considerable weight continues to descend 50 by gravity until it rests upon the face 22 of the cover 8 at which time the seat 17 is removed from the mouth of the bottle sufficiently to permit the contents of the bottle to flow out. The stem 18 which still projects 55 into the mouth of the bottle serves to distribute the stream which flows from the bottle uniformly into the alkaline solution in the reservoir and also to restrict its flow. By adjusting the sleeve 13 relatively to the 60 flange 12 any desired space may be provided between the seat 17 and the mouth of the bottle when the extinguisher is inverted

thereby providing a suitable regulation which will enable the apparatus to generate gas more or less gradually according to the 65 character of the chemicals used or other conditions. The liquid in the reservoir is forced by the pressure of the gas thus generated through the hose 23 which leads from near the bottom of the extinguisher 70 when the latter is inverted and in operative position.

By thus providing means for inclosing and projecting the stem 18 of the stopper-distributer at all times the breaking or injuring of the distributer stem is avoided and the proper operation of the distributer device insured. This is very important for the reason that if the acid is permitted to flow 75 too freely into the alkaline an excessive 80 pressure is generated which will either discharge the contents of the reservoir too quickly or possibly break the reservoir.

It will be understood that the embodiment of the invention disclosed herein is 85 illustrative merely and that various other means may be provided for preventing breakage of or injury to the stem 18 of the stopper-distributer within the meaning and scope of the following claims.

Having fully described my invention what I claim as new and desire to secure by Letters Patent is:

1. A cage for a bottle stopper of a chemical fire extinguisher in which the stopper 95 for the acid bottle is provided with a central distributing stem adapted to enter the neck of the bottle, comprising a sleeve having means of attachment to the cover of the extinguisher, a series of depending arms provided at a distance from their ends with shoulders positioned to limit the movement of the stopper and to retain the stem within the boundary of said cage whereby breakage or injury to said stem when the cover is removed from the receptacle or replaced thereon will be avoided.

2. A cage for a bottle stopper of a chemical fire extinguisher in which the stopper for the acid bottle is provided with a central 110 distributing stem adapted to enter the neck of the bottle, comprising a sleeve having means of attachment to the cover of the extinguisher, a series of depending arms adapted to guide the stopper-distributer, 115 and means for limiting the movement of the stopper in position to retain the stem thereof within the boundary of said cage, whereby breakage or injury to said stem when the cover is removed from the receptacle or replaced thereon will be avoided.

In testimony whereof, I have signed my name to this specification.

WILLIAM H. BANFIL.
